UNITED STATES PATENT OFFICE.

GEORGE DE BRETON HAYES, OF CHETEK, WISCONSIN.

DESIGN FOR A DISPLAY-CABINET.

SPECIFICATION forming part of Design No. 27,904, dated November 23, 1897.

Application filed October 5, 1897. Serial No. 654,183. Term of patent 7 years.

To all whom it may concern:

Be it known that I, GEORGE DE BRETON HAYES, a citizen of the United States, residing at Chetek, in the county of Barron and 5 State of Wisconsin, have invented a new and original Design for Display-Cabinets, of which the following is a specification.

This invention relates to a new and original design for a display-cabinet; and it has for its 10 object to provide a design of this character that shall be both useful and ornamental.

The leading feature of the design resides in an upright body having a front open space, a series of interior parallel obliquely-disposed 15 compartments, and a step-like series of transverse panels arranged within said front open space at the front side of the compartments, said transverse panels being arranged at an inclination to a vertical plane, with the contiguous 20 panels disposed at right angles to each other and the uppermost panel at the front of each compartment being a transparent panel.

A minor feature of the design resides in providing the upright body at its front side and 25 centrally between the ends thereof with a central vertical partition - panel, a front open space at each side of said partition-panel, and the step - like series of transverse panels within each of said front open spaces.

An additional minor feature of the design 30 also resides in having the transparent or glass panels at the front side of each of the obliquely-disposed compartments formed of two sections or members.

In the drawings, Figure 1 is a perspective 35 view of a display-cabinet embodying the herein-described design. Fig. 2 is a vertical sectional view thereof on the line 2 2 of Fig. 1.

Referring particularly to the drawings, the 40 numeral 1 designates an upright body substantially rectangular in form and provided at its front side and centrally between its

ends with a central vertical partition-panel 2, having intermediate its upper and lower ends a forwardly-extending horizontal shelf-piece 3, and serving to provide the body with a front open space 4 at each side thereof. 45

At each side of the central partition-panel 2 the upright body 1 has arranged therein a series of parallel inclined shelves 5, between which shelves are inclosed substantially rectangular obliquely-disposed compartments 6, and at the front side of the series of obliquely-disposed compartments 6, within each open front space 4, the upright body 1 is provided 55 with a step-like series of transverse panels 7 and 8, said transverse panels 7 and 8 being arranged at an inclination to a vertical plane with the contiguous panels at right angles to each other. A pair of right-angularly-disposed panels 7 and 8 inclose the front side of each obliquely-disposed compartment 6, and the uppermost panel 8 for each of said compartments is a transparent glass panel and formed of two sections or members, as clearly 60 illustrated in Fig. 1 of the drawings.

While the essential features of the design have been specifically referred to, the upright body of the cabinet may be further provided at the front lower side thereof with oppositely-located vertically-disposed rectangular frame-panels 9 and at its front corner edges with ornamental rounded beading 10. 70

What I claim is—

The design for a display-cabinet herein 75 shown and described.

In testimony that I claim the foregoing as my own I have hereto affixed my signature in the presence of two witnesses.

GEORGE DE BRETON HAYES.
